UNITED STATES PATENT OFFICE

1,935,261

CONDITIONING OF YARN

Charles Friedrich Dulken, Arlington, N. J.

Application May 20, 1932, Serial No. 612,612, and
in Germany June 3, 1931

11 Claims. (Cl. 28—58)

This invention relates to a method of and apparatus for the conditioning of yarn. It is known to moisten the yarn bundles or bobbins which have been prepared in the spinning mill, because the yarn becomes very dry owing to the spinning process. The moistening is necessary in order that the yarn may retain its properties independently of the time of year, the locality, the duration of storage, and any alteration in temperature. It is also already known to add to the moistening liquid an anticeptic or preserving addition. Great difficulties have hitherto been experienced in attaining a complete and uniform penetration of the yarn bobbin by the moistening liquid.

In my co-pending United States patent application No. 422,273 of 21st January, 1930, I have already proposed a method and apparatus according to which the yarn bobbin is wound upon a hollow perforated core, and the liquid, or a mixture of air and liquid is forced outwards from the interior of the bobbin through the body of yarn. In the apparatus a number of yarn bobbins are treated simultaneously, and are connected to a common liquid supply pipe. This apparatus has the disadvantage that a distribution of the liquid to each individual body of yarn in equal quantities is difficult to attain.

The present invention supplements that method by measuring a definite quantity of moistening liquid for each individual yarn bobbin and forcing it through the body of yarn by means of compressed air. Each bobbin therefore receives exactly the desired moistening, as a result of which the quality of the product is greatly improved.

The process is preferably carried out by the measured quantity of liquid being sucked up by the compressed air, whereupon the mixture of liquid and air penetrates through the body of yarn. The liquid may however alternatively be moved forward by compressed air acting upon it from behind. A combination of these two methods is also possible.

In the case of the method set forth in my co-pending application the liquid penetrates through the body of yarn in an outward direction. According to the present improvement the liquid may alternatively flow inwards from the outside.

The apparatus for carrying out this process is characterized by the fact that for each individual yarn bobbin there is provided a measuring vessel which is to be filled from a reservoir, and from which a pipe leads to the carrying body

that receives the bobbin, to which a separate compressed air pipe also leads in each instance.

The apparatus is preferably so designed that the liquid pipe opens centrally in the interior of the compressed air pipe by means of a nozzle 60 in the manner of an injector, the mouthpiece of the injector being at the same time constructed in its upper portion as a carrying seat for the bobbin of yarn. While the apparatus according to my other invention, mentioned above, is intended for the simultaneous treatment of a plurality of yarn bobbins, by the present improvement a device is provided which is applicable both for the reception and treatment of a plurality of yarn bobbins and also for the reception 70 and treatment of a single yarn bobbin. This constructional form is particularly suitable for operating on a small scale. Further details of the invention will be gathered from the following description and from the drawings and claims. 75

The invention is illustrated in various constructional examples in the accompanying drawings, in which

Figure 1 is a longitudinal section through apparatus according to the invention for treating 80 a single bobbin of yarn, the liquid being forced outwards from the interior of the bobbin.

Figure 2 is a similar longitudinal section of a form of construction in which the liquid flows 85 inwards from the outside.

Figure 3 is a diagrammatic side view of apparatus according to the invention for the treatment of a plurality of yarn bobbins.

Figure 4 is a diagrammatic front view thereof, 90 and Figure 5 is a diagrammatic plan thereof.

Figure 6 is a longitudinal section through an individual moistener of the apparatus shown in Figures 3 to 5.

Fig. 6a is a fragmentary side elevational detail 95 of the arrangement shown in Fig. 6 showing particularly the use of a bar with a plurality of moisteners.

Figure 7 is a similar longitudinal section of another constructional form, and

Figure 8 is a plan of a part of Figure 7. 100

The constructional form of the invention shown in Figure 1 is intended for the treatment of a single bobbin. The individual treatment is particularly advantageous when it is a question 105 of moistening rather large bodies of yarn, particularly cross wound bobbins or conical bobbins. The apparatus according to Figure 1 is also suitable for operation on a smaller scale.

The moistening medium is supplied through 110

piping 1 from a measuring vessel. The contents of the measuring vessel may be adjusted in a known manner by means of a plunger, a diaphragm or otherwise.

5 The piping 1 opens in the foot 2 of the moistener, by means of a nozzle 3, which stands centrally in the vertical axis of the apparatus. Into the cavity in the foot 2 there opens at the side a pipe 4, which supplies compressed air, and is 10 equipped with a control valve or cock 5. The foot 2 of the apparatus is continued upwards in a spindle 6, which is designed to carry the bobbin of yarn. The spindle 6 has a central bore at the lower end, and is provided with lateral 15 outlet apertures 7. The entire arrangement acts as an injector. The yarn bobbin consists of an inner tube or sleeve 8, perforated on its periphery, made of cardboard or other suitable material, and the body of yarn 9 wound upon this tube. 20 The inner tube 8 is mounted in a fluid-tight manner at the bottom upon a conical transition part of the spindle 6. The spindle 6 and the tube 8 might alternatively be made conical throughout as shown for example in Fig. 7. 25 From the foot 2 of the moistener there extends sideways and upwards an arm 10, which is provided at the top with two positioning rings 11. Between these rings a bush or sleeve 12 is rotatably but non-slidably fitted. To a pin 13 30 on the bush 12 is pivoted a plate 14, to the under side of which is secured a sealing stopper 15 of indiarubber or the like. The stopper 15 bears upon the upper end of the yarn tube 8 in the working position and closes it in a fluid-tight manner. To the bush 12 is rigidly secured a carrying arm 16, which has at its free end a pivot 17 for a hand lever 18. The pivot 17 is located approximately in the longitudinal axis of the spindle 6. With the lever 18 a cam 19 35 is integral, which acts against the pressure plate 14. The cam 19 is so shaped that when the hand lever 18 is rotated in a clockwise direction it acts first as an eccentric upon the plate 14, and thereby presses the tube 8 down firmly and 40 seals it at both ends. Upon further rotation of the lever 18 the cam 19 passes over the plate 14 with a portion of its surface which is concentric with the pivot 17, so that the pressure upon the yarn bobbin is no longer increased, but 45 the lever locks itself. Upon still further rocking, the lever 18 pushes against a control rod 20, which is longitudinally slidable in a guiding arm 21 secured to the foot 2, and presses this rod downwards. The lower end of the control rod 20 50 is pivotally connected with the positioning lever of the valve 5, so that the valve is opened. At the same time a spring 22 is compressed.

The apparatus acts in such a way that, after the mounting of the yarn bobbin to be moistened, 60 the sealing of the sleeve 8 at the top and bottom is first effected, and only then is the compressed air pipe 4 opened. The compressed air flows out and sucks up the liquid from the measuring vessel, whereupon the mixture of liquid and 65 air moves through the bores of the spindle 6 and the perforations of the sleeve 8 into the yarn body 9, which it penetrates radially outwards from inside. Only the liquid specially measured for this one bobbin is sucked up and forced through, 70 so that the bobbin is moistened exactly to the extent desired in all its parts. An excellent effect is thereby produced.

Furthermore the operation of filling and emptying the measuring vessel may be positively 75 connected, in a manner known in itself, with the

actuating of the lever 18 and the control rod 20, in such a way for example that when the lever 18 is raised, that is to say, when the air valve is closed and the yarn bobbins released, a measuring vessel of adjustable capacity is filled with the moistening liquid, and when the lever 18 is depressed, that is to say, when the body of yarn is pressed down and the air valve is opened, the measuring vessel is emptied into the liquid pipe. The following arrangement is also advantageous.

80 For the purpose of increasing the production two of the individual appliances described are placed side by side and are operated alternately by one worker. These two appliances then have a common liquid measuring device, which may be provided with two measuring chambers, separated by a diaphragm, actuated alternately, and adapted to be connected in a manner known in itself with the two moistening appliances. The 85 constructional form according to Figure 2 is distinguished from the one described by the fact that the moistening liquid does not flow through the body of yarn in an outward direction from the inside but in the opposite direction. The lower portion of the moistener agrees with that of Fig- 90 ure 1. The supply pipe for the liquid is marked 31, the outlet nozzle 33, the compressed air pipe 34, and the control valve thereof 35. The foot 32 of the device widens out in an upward direction to a 95 cylindrical or other casing, which may have a 100 double wall. In the latter case the outer wall 36 is not perforated, while the inner wall 37 and the inner bottom 38 are provided with numerous perforations. The lid 39 of the casing, which closes in a fluid-tight manner all round, is hinged, and 105 has in the middle on its under side a stopper or plug 40 of indiarubber or the like. The lower end of the tube 41 bears in a fluid-tight manner upon a projection 42 in the base of the casing. The 110 stopper 40 is longitudinally bored through, and 115 the lid 39 is bored through in the middle. These bores form an air vent. On the side of the casing 36 a lever 43 is rotatably mounted about a pivot 44. The lever 43 is equipped with a hook 45, which can engage over a pin 46 which is carried by two lateral lugs or projections on the lid 39. The pin 46 is again eccentrically shaped in such a way that it at first tends to press the lid 39 down firmly when the lever 43 is moved in an anti-clockwise direction. The inner portion of 120 the hook 45 is however concentric with the pivot 44. The lever 43 is again connected by a coupling rod 47 with the lever 48 of the valve 35.

125 After the bobbin of yarn has been inserted in the container the lid 39 is closed. This may be 130 provided round the margin with sealing means, 33' (Fig. 2). The vessel is hereby sealed while the indiarubber stopper 40 at the same time presses down the tube 41 of the yarn bobbin against the projection 42 so as to close the lower 135 end of the tube in a fluid-tight manner. Only after this has been done is the valve 35 opened, by further shifting of the lever 43. The compressed air sucks in the moistening liquid, and the mixture passes into the hollow space between 140 the outer wall 36 of the vessel and the inner wall 37 and bottom 38. The escaping mixture penetrates through the body of yarn in an inward direction, the air present in the vessel and in the body of yarn being able to escape through 145 the duct in the indiarubber stopper 40. The body of yarn is therefore again accurately moistened to the desired extent.

150 After the termination of the moistening, and before the lid 39 is opened again, any pressure pre-

vailing in the interior of the vessel may preferably be relaxed.

The form of construction of the invention illustrated in Figures 3 to 5 is intended for the simultaneous treatment of a plurality of bobbins of yarn. The main parts are only diagrammatically indicated.

From a reservoir 50 the moistening liquid flows to a measuring vessel 51, by natural descent for example.

From the measuring vessel 51 the liquid passes into an elongated distributing vessel 52, which is subdivided by partitions into a rather large number of individual cells or compartments 53. For each yarn bobbin one such cell 53 is provided. The partitions are interrupted at their lowest points by apertures 54, so that the liquid adjusts itself to the same height in all the cells 53 by the principle of communicating tubes. Each cell 53 is provided at the top with a little pouring tube 55. The distributing vessel is lodged in a long receiving vessel 56 and is rotatable about its longitudinal axis. The receiving vessel 56 is also subdivided by partitions 57 into individual cells equal in number to the cells 53. From each of these cells a pipe 58 leads to a different moistener upon the machine frame. When the vessel 52 is tilted about its longitudinal axis each cell 53 pours its contents, which are equal in every case, into a cell in the vessel 56. To each yarn bobbin there is therefore supplied by its particular pipe 58 exactly the same accurately measured quantity of liquid.

The moisteners themselves are indicated as a whole in Figures 3 to 5 by 59, and are arranged in three parallel straight rows. The connecting pipes 58 which convey the liquid to the moisteners 59, are shown broken off in Figure 4 for the sake of clearness, while in Figure 5 only a few of them are shown. The pipes 58 open in the feet of the individual moisteners in the manner illustrated at 1 and 31 respectively in Figures 1 and 2. To the feet of the moisteners there also lead the compressed air pipes 60, which are supplied with air by a main pipe.

Figure 6 shows the arrangement of an individual moistener. By 61 is illustrated a horizontal bar of the machine frame, on to which the foot 62 of the moistener is secured with a screw. In this foot the liquid pipe 58 opens. The end of this pipe is closed by an exchangeable nozzle 63. The nozzle 63 is again located in a chamber in the manner of an injector, in which there furthermore opens laterally the compressed air pipe 60. In the latter may be interposed a valve 64, which establishes communication with the main pipe 92. Upon the base body 62 of the moistener is again screwed at the top a longitudinally bored spindle 65, over which the perforated tube 66 of the yarn body 67 is slipped. The tube 66 is pressed firmly on to its seat by a bar 68, with an india-rubber stopper 69. The bar 68 runs longitudinally through the machine and serves at the same time for pressing down a plurality of yarn tubes as indicated diagrammatically in Fig. 6a. When the compressed air pipe 60 opens, the air sucks in the quantity of liquid poured out in the distributor 56 and forces it through it outwards through the body of yarn from the interior.

The various cocks of the plant, and also the gear for tilting the distributor 56, are preferably coupled together in such a way that the entire operation proceeds in the prescribed sequence. For this purpose there is supported on the machine frame a shaft 90, with a handwheel 91 and

this shaft is connected by gearing 94 and sprocket wheels 95 and chain 96 with the rotatable stem 97 of the valve which controls the passage of liquid from the tank 51 to the tiltable vessel 52, the arrangement of the gearing, sprocket and chain wheels being such that on every fourth revolution of the hand wheel 91 the valve will be opened. In addition bevel gearing 98 is provided between the shaft 90 and the sprocket and chain device 100 which is connected with the tiltable vessel 52 so as to ensure of the proper tilting of this vessel in timed relation with the operation of the valve 90. Another sprocket and chain connection 100 is provided between the shaft 90 and the valve 101 which controls the passage of compressed air through the compressed air pipe 60. Further gearing 102 is provided between the shaft 90 and the stem of the valve 103 which controls the passage of compressed air from the pipe 92 to the pipes 58. By continuing the rotation of the hand-wheel 91 the following operations are positively brought about in their order:—Measurement of the quantity of liquid required for one charging of the machine in the measuring vessel 51; discharging the contents of the measuring vessel 51 into the distributing vessel 52; tilting the distributing vessel; opening the compressed air pipes 60; and ventilating the air pipes after completely forcing the liquid through the bodies of yarn, in order that the air pipes may be ready for the next operation. By this positive succession of the individual operations by means of a main controlling mechanism, faults in operating are avoided. Preferably each revolution of the hand-wheel 91 brings about a distinct operation.

In Figures 7 and 8 is illustrated a constructional form of moistener, which is primarily suitable for conical yarn bobbins. The conical spindle 70 is again secured with a screw upon the foot 62 of the moistener, as illustrated in Figure 6. The spindle 70 is longitudinally bored but is closed at the top. Moreover a number of radial bores 71 lead outwards with a downward inclination. The yarn tube 72 is provided with suitable perforations 73, which are preferably somewhat larger than the ducts 71. The yarn tube 72 is mounted in a fluid-tight manner upon the spindle 70, and is for this purpose pressed on to it. This has the advantage that the interior of the yarn tube 72 remains dry, and the whole of the moistening liquid penetrates directly into the yarn body 74. In order that the holes 73 may be exactly over the holes 71 the yarn tube 72 is provided at the bottom in its peripheral surface with a recess 75, which engages over a transverse pin 76 on the spindle 70.

Since the raised internal pressure during the moistening tends to lift the yarn bobbin off the spindle 70 a special device is provided for holding the yarn tube firmly on the spindle. The drawings illustrate the fastening device, which consists of grippers 77, which are rotatably mounted at the bottom of the spindle 70, and which can engage with their upper hooks in apertures 78 in the peripheral surface of the yarn tube 72. The grippers 77 are double levers, the lower arms of which slide in eccentric slots 79 in a positioning disc 80. By rotating the disc 80 through a small angle upon the foot of the spindle 70 the yarn tube 72 can thus be firmly pressed on to the spindle or uncoupled from it again.

In Figure 3 is also indicated a constructional form in which, from the main air pipe 92, there branches off an auxiliary air pipe 93, which is

divided at the top into the liquid pipes 58. When the liquid has been distributed into the pipes 58, air pressure can be admitted behind the liquid columns by opening the pipe 93. This pressure effect may be added to the injector-like suction effect of the pipes 60. The arrangement may of course be such that only the pressure effect behind the columns of liquid comes into action. The discharge of the air from the pipe 93 into the distributing vessel 56 is prevented by non-return valves 58' in the pipes 58 shown diagrammatically in Fig. 3.

What I claim is:—

1. Apparatus for conditioning yarn wound into bobbins, comprising a measuring vessel for each individual yarn bobbin, a reservoir for supplying moistening liquid to the individual measuring vessels, carrying bodies for the individual yarn bobbins, separate pipes for conveying liquid from the individual measuring vessels to the individual carrying bodies, and separate compressed air pipes leading to the individual carrying bodies.

2. Apparatus for conditioning yarn wound into bobbins, comprising a measuring vessel for each individual yarn bobbin, a reservoir for supplying moistening liquid to the individual measuring vessels, carrying bodies for the individual yarn bobbins, separate pipes for conveying liquid from the individual measuring vessels to the individual carrying bodies, and separate compressed air pipes leading to the individual carrying bodies, the pipes for liquid opening centrally inside the compressed air pipes in such a manner as to form injectors, a carrying seat for the yarn bobbin on the upper part of each of the carrying bodies, and an injector mouthpiece adapted to discharge air and water through the carrying seat.

3. Apparatus for conditioning yarn wound into bobbins, comprising a measuring vessel for each individual yarn bobbin, a reservoir for supplying moistening liquid to the individual measuring vessels, carrying bodies for the individual yarn bobbins, separate pipes for conveying liquid from the individual measuring vessels to the individual carrying bodies, and separate compressed air pipes leading to the individual carrying bodies, the pipes for liquid opening centrally inside the compressed air pipes in such a manner as to form injectors, a carrying seat for the yarn bobbin on the upper part of each of the carrying bodies, an injector mouthpiece adapted to discharge air and water through the carrying seat, lever mechanism adapted to press the yarn bobbin into fluid-tight contact with its carrying seat, a valve controlling the supply of compressed air, and means such as a coupling rod connecting the lever mechanism with the valve in such a way that the valve is only opened after the yarn bobbin is resting firmly upon its seat.

4. Apparatus for conditioning yarn wound into bobbins, comprising a measuring vessel for measuring the quantity of moistening liquid required for an individual yarn bobbin, a carrying body for an individual yarn bobbin, a pipe for conveying liquid from the measuring vessel to the carrying body, a pipe for supplying compressed air to the carrying body, the pipe for liquid opening centrally inside the compressed air pipe in such a manner as to form an injector, a carrying seat for the yarn bobbin on the upper part of the carrying body, an injector mouthpiece adapted to discharge air and water through the carrying seat, lever mechanism including a cam comprising an eccentric element adapted to press the

yarn bobbin into fluid-tight contact with its carrying seat and a concentric element adapted to produce a self-locking effect, a valve controlling the supply of compressed air, and means such as a coupling rod connecting the lever mechanism with the valve in such a way that the valve is only opened after the yarn bobbin is resting firmly upon its seat, and the concentric element of the cam has come into operation.

5. Apparatus for conditioning a plurality of yarn bobbins simultaneously, comprising a tiltably supported elongated distributing vessel, partitions subdividing the distributing vessel into a number of compartments corresponding to the number of bobbins to be treated, the partitions being formed with apertures at their lowest points by which the compartments all communicate with one another, a measuring vessel for supplying a predetermined quantity of moistening liquid to the distributing vessel, carrying bodies adapted to support the individual yarn bobbins and admit moistening fluid thereto, separate pipes for conveying liquid to the individual carrying bodies, each compartment of the distributing vessel being adapted to empty its contents into one of these pipes when the distributing vessel is tilted, and separate compressed air pipes leading to the individual carrying bodies.

6. Apparatus for conditioning yarn wound on tubes to form bobbins, comprising a measuring vessel for measuring the quantity of moistening liquid required for an individual yarn bobbin, a carrying body for an individual yarn bobbin, a pipe for conveying liquid from the measuring vessel to the carrying body, a pipe for supplying compressed air to the carrying body, a spindle mounted on the carrying body to carry the bobbin, latches rockably mounted in the spindle, the bobbin tube being formed with apertures adapted to engage with the latches, and a manually rotatable eccentrically slotted disc for oscillating the latches at will into a position in which they engage in the said apertures and into a position in which they are located wholly within the spindle.

7. Apparatus for conditioning yarn wound on tubes to form bobbins, comprising a measuring vessel for measuring the quantity of moistening liquid required for an individual yarn bobbin, a carrying body for an individual yarn bobbin, a pipe for conveying liquid from the measuring vessel to the carrying body, a pipe for supplying compressed air to the carrying body, a stopper of resilient impervious material such as india rubber adapted to be applied to the top of the bobbin tube, and means for pressing the stopper firmly on to the yarn tube against the pressure of the compressed air in the tube.

8. Apparatus for conditioning a plurality of yarn bobbins simultaneously, comprising a tiltably supported elongated distributing vessel, partitions subdividing the distributing vessel into a number of compartments corresponding to the number of bobbins to be treated, the partitions being formed with apertures at their lowest points by which the compartments all communicate with one another, a measuring vessel for supplying a predetermined quantity of moistening liquid to the distributing vessel, carrying bodies adapted to support the individual yarn bobbins and admit moistening fluid thereto, separate pipes for conveying liquid to the individual carrying bodies, each compartment of the distributing vessel being adapted to empty its contents into one of these pipes when the distributing vessel is tilted,

separate compressed air pipes leading to the individual carrying bodies, valves controlling the supply of compressed air, means for venting the compressed air remaining in the apparatus after the moistening liquid has been forced through the yarn, and switching plant adapted to bring about in the correct sequence the admission of the predetermined quantity of moistening liquid to the measuring vessel, the transfer of the contents of the measuring vessel to the distributing vessel, the tilting of the distributing vessel, the opening of the compressed air valves, and the venting of the residual compressed air.

9. Apparatus for conditioning yarn wound on tubes to form bobbins, comprising a carrying vessel adapted to enclose an individual yarn bobbin in a fluid-tight manner, a measuring vessel for measuring the quantity of moistening liquid required for an individual yarn bobbin, a pipe for conveying liquid from the measuring vessel to the carrying vessel, a pipe for supplying compressed air to the carrying vessel, means for admitting the liquid and compressed air to the space between the external surface of the bobbin and the internal surface of the carrying vessel, the bobbin tube being perforated to enable compressed air that has passed inwards through the yarn to escape into it, and means for sealing the ends of the bobbin tube against the compressed air in the interior of the carrying vessel, the said sealing means and the carrying vessel being formed with apertures registering with one another through which air can escape from the interior of the bobbin tube to the atmosphere.

35 10. Apparatus for conditioning yarn wound on tubes to form bobbins, comprising a double-walled carrying vessel adapted to enclose an individual yarn bobbin in a fluid-tight manner, the inner wall of the carrying vessel being perforated, a measuring vessel for measuring the quantity of moistening liquid required for an individual yarn bobbin, a pipe for conveying liquid from the measuring vessel to the carrying vessel, a pipe for supplying

for supplying compressed air to the carrying vessel, means for admitting the liquid and compressed air to the space between the double walls of the carrying vessel, the bobbin tube being perforated to enable compressed air that has passed inwards through the yarn to escape into it, and means for sealing the ends of the bobbin tube against the compressed air in the interior of the carrying vessel, the said sealing means and the carrying vessel being formed with apertures registering with one another through which air can escape from the interior of the bobbin tube to the atmosphere.

11. Apparatus for conditioning yarn wound on tubes to form bobbins, comprising a double-walled carrying vessel adapted to enclose an individual yarn bobbin, the inner wall of the carrying vessel being perforated, a lid adapted to close the carrying vessel in a fluid-tight manner, a stopper in the middle of the lid adapted to seal the upper end of the bobbin tube in a fluid-tight manner from the interior of the carrying vessel, the lid and the stopper being formed with apertures through which the interior of the bobbin tube communicates with the atmosphere, a measuring vessel for measuring the quantity of moistening liquid required for an individual yarn bobbin, a pipe for conveying liquid from the measuring vessel to the carrying vessel, a pipe for supplying compressed air to the carrying vessel, a valve controlling the supply of compressed air, means for venting the compressed air remaining in the apparatus after the moistening liquid has been forced through the yarn, and lever mechanism for pressing the lid and stopper firmly on to the carrying vessel and bobbin tube and subsequently opening the compressed valve, and same lever mechanism being adapted, when actuated in the reverse direction, to close the compressed air valve, then vent the compressed air remaining in the apparatus, and then release the lid and stopper.
